CLAIM

The ornamental design for an electronic document reader, as shown and described.

DESCRIPTION

FIG 1 is a front elevational view of a first embodiment of the electronic document reader of the present design;

FIG 2 is a rear elevational view of the electronic document reader of FIG. 1;

FIG 3 is a left side elevational view of the electronic document reader of FIG. 1;

FIG 4 is a bottom side elevational view of the electronic document reader of FIG. 1; and,

FIG 5 is a front, left side, and bottom side perspective view of the electronic document reader of FIG. 1.

1 Claim, 2 Drawing Sheets

Matter enclosed in heavy brackets [ ] appears in the original patent, but forms no part of this reissue; matter printed in italics indicates the additions made by reissue.
